(57) **CLAIM**

The ornamental design for a children's ride-on vehicle, as shown and described.

DESCRIPTION

FIG. 1 is an isometric view of an embodiment of a children's ride-on vehicle showing the claimed design.

FIG. 2 is a left side elevation view of the vehicle of FIG. 1.

FIG. 3 is a right side elevation view of the vehicle of FIG. 1.

FIG. 4 is a top plan view of the vehicle of FIG. 1.

FIG. 5 is a rear elevation view of the vehicle of FIG. 1.

FIG. 6 is an isometric view of another embodiment of a children's ride-on vehicle showing the claimed design.

FIG. 7 is a left side elevation view of the vehicle of FIG. 6.

FIG. 8 is a right side elevation view of the vehicle of FIG. 6.

FIG. 9 is a top plan view of the vehicle of FIG. 6; and, FIG. 10 is a rear elevation view of the vehicle of FIG. 6. The bottom of the vehicle forms no part of the claimed design.
